UNITED STATES PATENT OFFICE.

HENRY D. OBERDORFER, OF QUINCY, ILLINOIS.

DESIGN FOR AN EASEL.

53,516.

Specification for Design.

Patented July 8, 1919.

Application filed March 31, 1919. Serial No. 286,579. Term of patent 3½ years.

To all whom it may concern:

Be it known that I, HENRY D. OBERDORFER, a citizen of the United States, residing at Quincy, Adams county, and State of Illinois, have invented a new, original, and ornamental Design for Easels, of which the following is a specification, reference being had to the accompanying drawing, forming part thereof.

The drawing shows—

In Figure 1 a front elevation; and
In Fig. 2 a side elevation of my new design of an easel.

I claim:

The ornamental design for an easel, substantially as herein shown.

In testimony whereof I affix my signature.
HENRY D. OBERDORFER.
